[57] CLAIM

The ornamental design for a french fry, as shown and
described.

DESCRIPTION

FIG. 1 is a top perspective view of a french fry showing
my new design;

FIG. 2 is a top plan view thereof, the undisclosed bottom
being the same;

FIG. 3 is a front end elevational view thereof, the undis-
closed rear end being unadorned and having the shape
as indicated in FIG. 2.

FIG. 1

FIG. 3

FIG. 2
